(57) **CLAIM**

The ornamental design for a combination bar tool, as shown and described.

DESCRIPTION

FIG. 1 is a top, front, right side perspective view of a combination bar tool of the present invention, consisting of a stirring spoon, bottle opener, cork screw, measuring cup, squeezer and ice bucket with lid;

FIG. 2 is a front elevation view thereof;

FIG. 3 is a top plan view thereof;

FIG. 4 is a cross-section view taken along the line 4-4 in FIG. 2;

FIG. 5 is a top, rear right side perspective view of the stirring spoon, bottle opener, and cork screw portion of the combination bar tool of FIG. 1;

FIG. 6 is a right side elevation view thereof;

FIG. 7 is a front elevation view thereof;

FIG. 8 is a top plan view thereof;

FIG. 9 is a cross-section view taken along the line 9-9 in FIG. 7;

FIG. 10 is a top, front, right side perspective view of the stirring spoon, bottle opener, cork screw portion combined with the measuring cup and squeezer portions of the combination bar tool of FIG. 1;

FIG. 11 is a front elevation view thereof;

FIG. 12 is a top plan view thereof;

FIG. 13 is an exploded top, front, left side perspective view thereof;

FIG. 14 is a cross-section view taken along the line 14-14 in FIG. 11;

FIG. 15 is a top, rear, left side perspective view of the measuring cup portion of the combination bar tool of FIG. 1;

FIG. 16 is a bottom front left side perspective view thereof;
FIG. 17 is a front elevation view thereof;
FIG. 18 is a bottom plan view thereof;
FIG. 19 is a cross-section view taken along the line 19-19 in FIG. 17;
FIG. 20 is a top, side perspective view of the squeezer portion of the combination bar tool of FIG. 1;
FIG. 21 is a front elevation view thereof, the rear elevation view being identical;

FIG. 22 is a top plan view thereof;
FIG. 23 is a cross-section view taken along the line 23-23 in FIG. 21;
FIG. 24 is a top perspective view of the ice bucket and lid portion of the combination bar tool of FIG. 1;
FIG. 25 is a front elevation view thereof;
FIG. 26 is a side elevation view thereof, the opposing side elevation view being a mirror image; and,
FIG. 27 is a top plan view.
